UNITED STATES PATENT OFFICE.

JOSEPH B. MOWRY, OF CLEVELAND, OHIO, ASSIGNOR OF ONE-EIGHTH
TO EDWARD LINDMUELLER, OF CLEVELAND, OHIO.

STEAM-BOILER.

No. 826,519.

Specification of Letters Patent.

Patented July 17, 1906

Application filed August 23, 1905. Serial No. 275,432.

To all whom it may concern:

Be it known that I, JOSEPH B. MOWRY, a citizen of the United States, residing at Cleveland, in the county of Cuyahoga and State of Ohio, have invented certain new and useful Improvements in Steam-Boilers; and I do hereby declare the following to be a full, clear, and exact description of the invention, such as will enable others skilled in the art to which it appertains to make and use the same.

My invention relates to improvements in steam-boilers.

It has for its object, among others, to provide a construction which can be more easily and quickly erected, cleaned, and repaired than those now in use and which is capable of quickly getting up steam with the consumption of comparatively little fuel.

The invention consists of the features of construction and combinations of parts hereinafter described, and more particularly pointed out in the claims concluding this specification.

In the accompanying drawings, illustrating the preferred embodiment of my invention, Figure 1 is a side elevation of my boiler. Fig. 2 is a central vertical sectional view taken longitudinally of the fire-boxes. Fig. 3 is a vertical sectional view taken at right angles to Fig. 2. Fig. 4 is an elevation looking in the end of one of the fire-boxes, the end of said fire-box being broken away; and Fig. 5 is a cross-sectional view on the line $x-x$ of Fig. 2.

While the preferred embodiment of my invention is illustrated in the accompanying drawings and its construction and operation are described in this specification, the right is reserved to make such changes from the construction shown and described herein as the scope of the claims hereto appended will permit.

Referring more particularly to the drawings, I build the boiler over a pit 1 upon brick foundations 2. The fire-boxes 3 are arranged at either side of the pit opposite one another. The pit and body of the boiler are circular in form, while the oppositely-projecting fire-boxes make the base rectangular in form. The upper portion of the fire-boxes above the brickwork, which extends about half-way up above the grates 4, and the tops

of said fire-boxes are formed by double water-walls 5, which connect with the cylindrical upright water-wall 6 of the body of the boiler. Said water-walls are constructed of two metal plates held together at the proper distance apart by rivet-bolts 7. The edges of said walls are made by bending the inner plates flat upon the outer ones and riveting them securely together. The upright cylindrical water-wall 6 is made in two semicircular sections, the vertical edges of which are formed as just described and drawn together and secured by the requisite number of clamps 8. To the top of the vertical water-wall is secured the funnel-shaped cap 9, leading to the chimney.

Within the foundation-wall between the fire-boxes and above the pit is arranged a plate 10 about on a level with the grates. Another plate 11 is arranged above the plate 10 about on a level with the top of the brick walls of the fire-boxes and the bottom of the water-walls 5. Bridge-walls 12 are built across between each fire-box and the edge of the plate 11 to protect it from the fires. The steam-dome 13 is arranged centrally of the upper portion of the boiler, preferably extending above the water-wall and set away from said water-wall to leave a passage for the smoke from the fires. The bottom plate 14 of said dome and the plate 11 are both perforated, the perforations being arranged in concentric circles and those in the upper plates registering with those in the lower one. Between the perforations are arranged pipes 15. Another row of pipes 16 extend from the plate 11 upward outside the dome and enter said dome through its sides, as at 16^a, below the level of the water therein, which fills the tubes or pipes and the space or chamber formed between the plates 10 and 11, as well as the water-walls. One of the outer row of pipes 16 extends upward through the cap of the boiler and has connection, as at 17, with the dome below the water-level and at 18 above the level of the water, whereby the steam is carried off. A pipe 19 connects the upper portion of one part of the upright water-wall with said steam-pipe, so as to carry off any steam that accumulates in the upper part of said wall above the water-level. A similar pipe 20 connects the upper part of the other section of

the water-wall with the steam-dome. In order to insure the free circulation of the water from the water-walls 5 around the fire-boxes to the dome and inner tubes, a pipe 21 extends from the top of each fire-box through the upright water-walls 6 and opens on the dome below the water-level. The sides of said water-walls 5 around the fire-boxes are also connected with the chamber between the plates 10 and 11 by pipes 22. Said plate 10 is provided with hand-holes covered by plates 23, whereby the tubes or pipes extending from the plate 11 to the dome may be drawn down into the pit below the boiler for repairing or replacing. A hand-hole 24 is also arranged in the top of the steam-dome to provide for cleaning the same.

The advantage in making the upright water-wall in two sections is to facilitate the erection and repairing of the boiler. By means of my construction it is not necessary for a man to get inside to erect or repair the boiler; but all the riveting, &c., can be done from the outside, with a large saving of time and expense. The construction of the pit below also facilitates the work of repairing the tubes, as they may be drawn down into said pit instead of having to tear the top off the boiler and taking said tubes out at the top.

By the use of the metal water-walls as a casing for the boiler instead of masonry I am enabled to get up steam in a much shorter time with a saving in fuel. The heat in my boiler will commence to act upon the water at once, whereas in the old form of brick boxes a great deal of heat is wasted in heating the pile of bricks. Another disadvantage of the brick boxes is that they are continually cracking and falling down.

As shown in Fig. 3, I may employ a steam-blower for cleaning the soot out of the interior of the boiler. Said blower comprises an adjustable pin or rod 24, carrying a ball or spreader 25 at its end and mounted in a pipe 26, entering through the center of the plate 10. The handle 27 on the lower end of said pin may be turned to control the flow of the steam through said pipe 26 past the spreader. The steam is normally cut off from said pipe entirely by a valve (not shown) arranged outside the boiler.

Having thus described my invention, what I claim as new, and desire to secure by Letters Patent, is—

1. A boiler comprising a casing formed of a water-wall, a steam-dome arranged near the top, and a water-chamber near the bottom, within said casing pipes connecting said dome and chamber, a fire-box communicating with said casing, a water-jacket extending across the top and partially down the sides of said fire-box, pipes forming direct connection between said water-jacket and the dome and water-chamber and pipes for conveying steam

from the upper portion of the water-wall to 65 the steam-dome.

2. A boiler comprising a casing formed of a water-wall, a steam-dome arranged near the top, within, and spaced away from the sides of said casing, a fire-box having communication with said casing, a water-chamber extending across near the bottom of said casing below the passage from the fire-box to the casing, pipes connecting said chamber with the bottom of said dome, other pipes connecting said chamber with the sides of said dome, and a fire-box having communication with said casing, the products of combustion being forced to pass among said pipes and up around said dome to an outlet above it. 80

3. A boiler comprising a casing formed of a water-wall, a steam-dome arranged near the top, within, and spaced away from the sides of said casing, a water-chamber arranged near the bottom of said casing, pipes connecting 85 said chamber and dome, a fire-box having communication with said casing, a water-jacket extending across the top and partially down the sides of said fire-box, and pipes forming direct connection between said water-jacket and the dome and water-chamber, the products of combustion being forced to pass among the pipes connecting the water-chamber and dome and up around said dome to an outlet above it. 95

4. A boiler comprising a casing formed of a water-wall, a steam-dome arranged near the top, within, and spaced away from, the sides of said casing, a water-chamber arranged near the bottom of said casing, pipes connecting 100 said chamber with the bottom of said dome, other pipes connecting said chamber with the sides of said dome, one of said latter pipes extending up through the top of the casing for carrying off the steam, said pipe having communication with said dome, above the water-level, and with the upper portion of the water-wall, and a fire-box having communication with said casing. 105

5. A boiler comprising a cylindric casing formed of two upright semicircular sections of water-wall, connected at the edges, a steam-dome arranged near the top, and a water-chamber near the bottom, of said casing, pipes connecting said water-chamber and dome, a 110 fire-box arranged opposite each section of said water-wall, and a water-jacket around the upper portion of each of said fire-boxes, each of said water-jackets having communication with one of said sections of water-wall and with said steam-dome and water-chamber direct. 115

In testimony whereof I affix my signature in presence of two witnesses.

JOSEPH B. MOWRY.
